US00D790964S

(12) **United States Design Patent** (10) **Patent No.:** **US D790,964 S**
(45) **Date of Patent:** **** Jul. 4, 2017**

(54) **PACKAGING**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/565,702**

(22) Filed: **May 24, 2016**

(57) **CLAIM**

The ornamental design for packaging, as shown and described.

DESCRIPTION

FIG. 1 is a top front perspective view of packaging showing the claimed design according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

(Continued)

FIG. 8 is an exploded top front perspective view thereof, separating the upper portion of the packaging from the lower portion of the packaging;
 FIG. 9 is a front view of the lower portion of the packaging of FIG. 8;
 FIG. 10 is a rear view thereof;
 FIG. 11 is a left side view thereof;
 FIG. 12 is a right side view thereof;
 FIG. 13 is a top view thereof;
 FIG. 14 is a bottom view thereof;
 FIG. 15 is a top view thereof showing the packaging in an environment in which it may be used;
 FIG. 16 is a front view of the upper portion of the packaging of FIG. 8;
 FIG. 17 is a rear view thereof;
 FIG. 18 is a left side view thereof;
 FIG. 19 is a right side view thereof;
 FIG. 20 is a top view thereof;
 FIG. 21 is a bottom view thereof;
 FIG. 22 is a top front perspective view of packaging showing the claimed design according to a second embodiment;
 FIG. 23 is a front view thereof;
 FIG. 24 is a rear view thereof;
 FIG. 25 is a left side view thereof;
 FIG. 26 is a right side view thereof;
 FIG. 27 is a top view thereof;
 FIG. 28 is a bottom view thereof;
 FIG. 29 is an exploded top front perspective view thereof, separating the upper portion of the packaging from the lower portion of the packaging;
 FIG. 30 is a front view of the lower portion of the packaging of FIG. 29;
 FIG. 31 is a rear view thereof;
 FIG. 32 is a left side view thereof;
 FIG. 33 is a right side view thereof;
 FIG. 34 is a top view thereof;
 FIG. 35 is a bottom view thereof;
 FIG. 36 is a top view thereof showing the packaging in an environment in which it may be used;
 FIG. 37 is a front view of the upper portion of the packaging of FIG. 29;
 FIG. 38 is a rear view thereof;
 FIG. 39 is a left side view thereof;
 FIG. 40 is a right side view thereof;
 FIG. 41 is a top view thereof; and,
 FIG. 42 is a bottom view thereof.
 The broken lines in the figures show environment that forms no part of the claimed design.
